(57) **CLAIM**

The ornamental design for a SSD(Solid State Drive) memory device, as shown and described.

DESCRIPTION

FIG. 1 is a front perspective view of a SSD(Solid State Drive) memory device showing my new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof; and,

FIG. 8 is another perspective view thereof.

The evenly dashed broken lines in the figures depict portions of the SSD(Solid State Drive) memory device that form no part of the claimed design. The dot-dash lines define the boundary of the claimed design and form no part thereof.
